CLAIM

The ornamental design for a mounting rail, as shown and described.

DESCRIPTION

FIG. 1 is a top, front, right-side perspective view of a mounting rail.

FIG. 2 is a top, front, left-side perspective view thereof;

FIG. 3 is a bottom, back, right-side perspective view thereof;

FIG. 4 is a bottom, back, left-side perspective view thereof;

FIG. 5 is a front view thereof;

FIG. 6 is a back view thereof;

FIG. 7 is a right-side view thereof;

FIG. 8 is a left-side view thereof;

FIG. 9 is a top view thereof; and,

FIG. 10 is a bottom view thereof.

The dot-dashed broken lines indicate symbolic break lines in FIGS. 1-4 and 7-10. The break lines and portions of the article between the break lines form no part of the claimed design.

1 Claim, 10 Drawing Sheets
